JOHN RUPP, OF NEW YORK, N. Y., ASSIGNOR TO HIMSELF AND FREDERICK KIESER.

Letters Patent No. 65,950, dated June 18, 1867.

IMPROVEMENT IN DOUBLE-SEAMING MACHINE.

The Schedule referred to in these Letters Patent and making part of the same.

TO ALL WHOM IT MAY CONCERN:

Be it known that I, JOHN RUPP, of the city, county, and State of New York, have invented a new and improved Double-Seaming Machine; and I do hereby declare that the following is a full, clear, and exact description thereof, which will enable others skilled in the art to make and use the same, reference being had to the accompanying drawings, forming part of this specification, in which—

Figure 1 represents a side elevation of this invention.

Figure 2 is a sectional front elevation of the same, the line x x , fig. 3, indicating the plane of section.

Figure 3 is a horizontal section of the same, taken in the plane indicated by the line y y , fig. 1.

Figure 4 is a plan of the disk which supports the work detached.

Figures 5, 6, and 7 are diagrams, showing the work in different stages of completion.

Similar letters of reference indicate like parts.

This invention relates to certain improvements on that class of double-seaming machines on which Letters Patent have been granted to James Wilson, C. Green, and William Wilson, Jr., April 19, 1859.

This invention consists in a movable slide carrying a supporting plate, in combination with a metallic disk mounted upon a vertical shaft; in the arrangement of three or more cone-rollers in an annular rim, in combination with a rising and falling disk; and in the combination of a clamping-roller with burring-rollers and revolving disk, as will be hereinafter more fully described.

A represents a disk made of metal or any other suitable material, and mounted on a vertical axle, B, which has its bearings in arms C extending from the frame D, and the lower end of which is supported by a block, a, secured in a slide E, which moves up and down in a suitable guide-groove, b, in the frame D, and which can be raised by stepping on a treadle, F. This treadle connects with the slide by means of a lever and chain, or in any other suitable manner, and it is arranged in a convenient position for operation. On the shaft B is mounted a loose pulley, G, and a fast pulley, G', and these pulleys are in such a position that when said shaft is down the driving-belt runs on the loose pulley, but when the shaft is up the driving-belt passes from the loose to the fast pulley and causes the shaft to revolve. The disk A is provided with a dove-tailed groove, e, which extends diametrically through its centre and forms the guide for a slide, d, and from this slide rises a rod, e, on the top, of which is mounted a circular plate, f. The slide d is retained in the groove e by two latches, g, and if it is adjusted in the proper position the rod e forms a continuation of the shaft B. The plate f screws on the rod e, and a jam-nut, h, serves to lock it in the desired position. The body of the kettle or other vessel to be provided with a bottom is placed in a reverse direction on the disk A, and the plate f is adjusted so that its upper surface is on a level with the edge of said kettle or vessel, as shown in fig. 2. On the plate f is placed the blank of the bottom, and this blank is kept in a central position by three or more rollers, i, which are mounted on axles j, that have their bearing in suitable brackets, k, and said blank is clamped between said plate and a swivel-plate l, which revolves freely on the lower end of a rod, m. This rod is situated in line with the shaft B, and it slides up and down in an arm, n, on the top of the frame D, being subjected to the action of a weight or spring which depresses the swivel-plate l with sufficient force on the blank to hold the same between the two plates and to compel it to revolve with said plates. The brackets k are secured to an annular rim, H, which is secured to the frame D, and they are adjustable in a radial direction by suitable slots and screws. The rollers i in said brackets are provided with three or more speeds each, like cone-pulleys, and the smallest speeds, which are at the bottom, form the guides which bear against the edge of the blank and keep the same in a central position. The body of the vessel and the blank of the bottom, as the same are adjusted on the disk A, are in the form shown in fig. 5. When the disk A is raised by depressing the treadle F, the edge of the blank bears against the shoulders above the lowest speeds of the cone-rollers i, and its edge is turned down to the position shown in fig. 6. At this stage of the process the burring-roller o and the clamping-roller p are brought into action, and thereby the edge of the bottom is brought in the form shown in fig. 2. Said two rollers are mounted in a common carriage, q, which slides back and forth in a radial guide-way in the annular rim H. The clamping-roller p is secured to the inner end of a lever, r, which has its fulcrum on a pivot, s, and to which a tilting motion can be imparted by a cam, t, and crank, u. The burring-roller o is secured to the inner end of an

arbor, which has its bearing in the lower part of the carriage, and a lever, *r*, serves to move said carriage back and forth in the radial guide-way. By the action of the burring-roller the edge of the bottom is turned as shown in fig. 2, and by the clamping-roller it is firmly pressed up against the rim of the body of the vessel. After this has been accomplished the treadle is still further depressed, and by the action of the second shoulders of the cone-rollers *i* the edge of the bottom, together with the rim of the body of the vessel, is forced into the position shown in fig. 7, and a double seam is finished by the action of the largest speeds of the cone-rollers. By these means the bottoms can be attached to the bodies of tin vessels with the greatest ease and facility. By the application of the movable slide, in combination with the disk *A*, the operation of introducing and removing the vessels is materially facilitated, and by the use of three or more rollers acting simultaneously on the edges of the bottoms, said bottoms are kept in the centre, and the operation is effected without requiring particular attention.

I disclaim everything claimed and described in the patent of Wilson, Green, and Wilson hereinbefore mentioned.

What I claim as new, and desire to secure by Letters Patent, is—

1. The movable slide *d* carrying the supporting plate *f*, in combination with the disk *A*, constructed, arranged, and operating substantially as and for the purpose described.
2. The arrangement of three or more cone-rollers *i*, in the annular rim *H*, in combination with the rising and falling disk *A*, constructed, arranged, and operating substantially as and for the purpose set forth.
3. The clamping-roller *p*, in combination with the burring-roller *o*, and disk *A*, constructed, arranged, and operating substantially as and for the purpose described.

The above specification of my invention signed by me this 28th day of August, 1866.

JOHN RUPP.
